(57) **CLAIM**

The ornamental design for a folding sink, as shown and described.

DESCRIPTION

FIG. 1 is a front, right, top perspective view of a folding sink, showing my new design;

FIG. 2 is a rear, left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of detail 9 in FIG. 5;

FIG. 10 is an enlarged view of detail 10 in FIG. 7; and,

FIG. 11 is an enlarged view of detail 11 in FIG. 8.

The dashed broken lines in the figures illustrate portions of the folding sink that form no part of the claimed design.

The short-short-long dashed broken lines immediately adjacent to the claimed areas in the views represent the boundaries of the design and form no part of the claimed design.

The dash-dot-dash broken lines are for notating enlarged views and form no part of the claimed design.
